UNITED STATES PATENT OFFICE.

DANIEL S. TUTHILL, OF NEWBURG, NEW YORK, ASSIGNOR OF ONE-HALF TO
B. H. DUROIS AND J. J. B. DUROIS, BOTH OF LEADVILLE, COLORADO.

RAILROAD-RAIL.

SPECIFICATION forming part of Letters Patent No. 350,089, dated September 28, 1886.

Application filed June 10, 1886. Serial No. 204,762. (No model.)

To all whom it may concern:

Be it known that I, DANIEL S. TUTHILL, of Newburg, in the county of Orange, and in the State of New York, have invented certain new and useful Improvements in Railroad-Rails; and I do hereby declare that the following is a full, clear, and exact description thereof, reference being had to the accompanying drawings, in which—

10 Figure 1 is a perspective view of the engaging ends of my rails separated from each other. Fig. 2 is a like view of the same united, and Fig. 3 is a cross-section upon line $x-x$ of Fig. 2.

Letters of like name and kind refer to like parts in each of the figures.

The design of my invention is to enable rails to be so connected at their ends as to prevent the independent vertical movement of either, without interference with such longitudinal movement as results from the expansion and contraction of the metal; and to this end said invention consists in a railroad-rail which is provided upon one end with a longitudinal projecting tongue and has its head at such point formed upon an oblique line, in combination with a rail which has an obliquely-cut head, and is provided with a groove that is adapted to receive and contain the tongue of the opposite rail, substantially as and for the purpose hereinafter shown.

It consists, further, in a railroad-rail which at one end has its head formed upon a horizontally-oblique line and its foot formed upon a line having a right angle to the length of said rail, and is provided with a tongue that projects longitudinally forward from and is a continuation of its web, in combination with a second rail which has the ends of its head and foot formed, respectively, upon diagonal and right-angle lines, and within its web is provided with a groove that corresponds to and is adapted to receive the web-tongue of the opposite rail, substantially as and for the purpose hereinafter set forth.

45 It consists, finally, in a railroad-rail which at one end has its head formed upon a horizontally-oblique line and its foot formed upon a line having a right angle to the length of said rail, and is provided with a tongue that projects longitudinally forward from and is a con-

tinuation of its web, a rail which has the ends of its head and foot formed, respectively, upon diagonal and right-angle lines, and within its web is provided with a groove that corresponds to and is adapted to receive the web-tongue of 55 the opposite rail, in combination with each other and with means, substantially as described, whereby said rails may have their intersecting ends confined in relative lateral position, substantially as and for the purpose 60 hereinafter specified.

In the carrying of my invention into practice I employ a rail, A, which has any usual construction, and at one end of the same cut away the foot a for about four inches, leaving 55 its end square, as before, and in a like manner cut away its head a' , but form the end of the same upon a line that preferably has horizontally an angle of about forty-five degrees to the longitudinal axis of said rail. By thus cutting 70 away the head and foot of said rail the projecting portion of the web a^2 forms a tongue, a^3 , as shown. The rail A' which is to be connected with the rail A has the ends of its head a^4 and foot a^5 formed upon lines that correspond to 75 the angles of the head a' and foot a of said rail A, while its web a^6 is cut away, so as to form a groove, a^7 , which corresponds to and is adapted to receive the tongue a^3 , so that when 80 said rails are placed together, as shown in Fig. 8c 2, their said ends interlock and abut in such manner as to prevent all independent vertical motion of either, and to render said rails practically solid at their junction. In consequence 85 of the horizontally-oblique joint at the point where the rail-heads a' and a^4 meet, a car-wheel passing over the same has a bearing upon each rail along the entire length of the joint, so that 90 there is no possibility of a jolt at such point, as the bearing by such construction is continuous instead of being interrupted, as in the usual construction of rails. With the rails thus constructed fish-bars B and B, united by bolts C in the usual manner, are preferably employed; but in their place any desired means 95 may be used for insuring the relative lateral position of the ends of said rails.

Having thus described my invention, what I claim is—

1. A railroad-rail which is provided upon 100

one end with a longitudinal projecting tongue and has its head at such point formed upon an oblique line, in combination with a rail which has an obliquely-cut head, and is provided with 5 a groove that is adapted to receive and contain the tongue of the opposite rail, substantially as and for the purpose shown.

2. A railroad-rail which at one end has its head formed upon a horizontally-oblique line 10 and its foot formed upon a line having a right angle to the length of said rail, and is provided with a tongue that projects longitudinally forward from and is a continuation of its web, in combination with a second rail

15 which has the ends of its head and foot formed, respectively, upon diagonal and right-angle lines, and within its web is provided with a groove that corresponds to and is adapted to receive the web-tongue of the opposite rail, substantially as and for the purpose set forth.

3. A railroad-rail which at one end has its head formed upon a horizontally-oblique line 20

and its foot formed upon a line having a right angle to the length of said rail, and is provided with a tongue that projects longitudinally forward from and is a continuation of its web; a rail which has the ends of its head and foot formed, respectively, upon diagonal and right-angle lines, and within its web is provided with a groove that corresponds to and is adapted to receive the web-tongue of the opposite rail, in combination with each other and with means, substantially as described, whereby said rails may have their intersecting ends confined in relative lateral position, substantially as and for the purpose specified. 25

In testimony that I claim the foregoing I have hereunto set my hand this 5th day of June, A. D. 1886.

DANIEL S. TUTHILL.
